NICHOLAS WITSCH, OF JERSEY CITY, NEW JERSEY, ASSIGNOR TO THE AMERICAN LITHOGRAPHIC COMPANY, OF NEW YORK, N. Y.

DESIGN FOR A PRINT OR PATTERN FOR CIGAR-BOXES.

SPECIFICATION forming part of Design No. 26,208, dated October 20, 1896.

Application filed September 14, 1896. Serial No. 605,822. Term of patent 7 years.

To all whom it may concern:

Be it known that I, NICHOLAS WITSCH, a citizen of the United States, residing at Jersey City, in the county of Hudson and State of New Jersey, have invented and produced a new and original Design for an Ornamental Print or Pattern for Cigar-Boxes; and I do hereby declare the following to be a full, clear, and exact description of the same, reference being had to the accompanying drawing, forming a part thereof.

The design is placed upon a cigar-box, as shown in the drawing.

Said design consists of an oval panel having an ornamental scrollwork surrounding it and containing a portrait. To the left of the panel is the American flag draped over a portion of the scrollwork, and in the background to the

left is shown a portion of the bulwarks and deck of a ship and two figures of men in civilian's dress. To the right of the panel in background is shown a portion of the ramparts of a fort having a flagstaff from which is flying the American flag. A cannon is shown on the ramparts, manned by three soldiers.

I claim—

The design for an ornamental print or pattern for cigar-boxes, substantially as shown and described.

In testimony whereof I affix my signature in presence of two witnesses.

NICHOLAS WITSCH.
